UNITED STATES PATENT OFFICE.

OTTO WILLIAM MEISSNER, OF WESTMOUNT, QUEBEC, CANADA.

SHAFT-ROTATING MEANS.

No. 903,301.

Specification of Letters Patent. Patented Nov. 10, 1908.

Application filed April 20, 1908. Serial No. 428,178.

To all whom it may concern:

Be it known that I, OTTO WILLIAM MEISSNER, of Westmount, Province of Quebec, Canada, have invented certain new and useful Improvements in Shaft-Rotating Means; and I do hereby declare that the following is a full, clear, and exact description of the same.

My invention although applicable to any shaft required to be rotated by manual power is particularly adaptable to the operating shaft of the hand brake mechanism of railway cars, and it has for its object to provide a device of this nature which will in itself present both the means whereby the hand power can be applied and the abutment from which the pressure is derived, without the necessity of the operator depending upon his foot hold for the purpose, such abutment serving also as a means for locking the shaft against retrogression.

The invention may be said briefly to consist of the combination and arrangement of parts hereinafter described and pointed out in the claims.

For full comprehension, however, of my invention reference must be had to the accompanying drawings forming a part of this specification, wherein corresponding reference numerals indicate the same parts, and wherein

Figure 1 is a side elevation of the shaft of a hand brake mechanism for railway cars with my improved operating mechanism applied thereto; Fig. 2 is a horizontal sectional view taken on line B B Fig. 1; Fig. 3 is a vertical sectional view taken on line C Fig. 1; Fig. 4 is a plan view, partly in section, of the abutment pawl; and Fig. 5 is an edge elevation thereof.

A portion of the frame of the car is indicated at b, and c is the hand rotated shaft operatively connected to the brake mechanism not shown. The shaft has a ratchet wheel d mounted rigidly thereon near its upper end, and it is inclosed in a shallow metal box e pivotally connected to a plate f bolted, as at g, to the overhanging portion of the frame b, such box being formed with a handle k and an internal tooth m, the latter being adapted to engage the teeth of the ratchet wheel and be disengaged therefrom when the box is moved to the respective positions shown in full and dotted lines Fig. 4. This ratchet wheel, the pawl constituted by the pivoted box e and tooth, and the handle k

afford means whereby the shaft c can be held against rotation in one direction. The means for rotating the shaft in the opposite direction consists of a spanner n and a polygonal portion o of the shaft, the spanner being formed with a pair of trunnions p upon its opposite sides and presenting oval heads r preferably parallel to the body of the spanner. These trunnions bear in diagonal slots 60 in the upwardly turned ends t of a pair of straps u and v conjointly encircling a flanged collar w keyed to the shaft, while the strap u is formed with a lip x and a tubular stud y with diminished or contracted end z, and the strap v has a transverse slot 2 to receive the lip x and a hole 4 for the diminished end of the stud y. These parts are secured together in the form of a strap encircling the flanged collar by inserting the lip x into the slot 2 70 and the diminished end z of the stud y into the hole 4 and expanding the protruding end of z, thus obviating the necessity of a bolt, nut, and distance piece at this point, although a hole 5 through the strap u in line 75 with the stud y enables a bolt and nut to be used in the event of the stud being broken off.

The oval heads r and diagonal slots s enable the spanner to be readily set in place before the straps are fastened together, and should one of the upturned strap ends be broken off the spanner will still be retained in position by the remaining strap end.

Operation: The operation of turning the shaft by my improved rotating gear is as follows:—The operator takes hold of the spanner with one hand and the handle k of the pawl with the other, and he pushes against the pawl while he pulls upon the spanner thus obtaining his purchase or abutment, (through the pawl and ratchet wheel) in the shaft, and as he disengages the spanner and returns the same, by his right hand, for a new operation, he retains the shaft 95 against retrograde rotation with his left hand.

What I claim is as follows:

1. The combination with a shaft to be rotated and manually operated means for rotating the same, of means for preventing retrograde rotation of the shaft during the intermissions, such last mentioned means presenting a hand-hold whereby the operator can obtain the necessary purchase to enable him to operate the said first mentioned means.

2. The combination with a shaft to be ro-

tated, a stationary part adjacent thereto and manually operated means for rotating the same, of a ratchet wheel mounted rigidly upon the shaft, and a pawl pivotally connected to the stationary part and adapted to engage the ratchet wheel, such pawl having a hand-hold formed integrally therewith and furnishing the necessary purchase to enable an operator to operate the said first mentioned means.

3. The combination with a shaft to be rotated, a stationary part adjacent thereto and manually operated means for rotating the same, of a ratchet wheel mounted rigidly upon the shaft, and a pawl of box-form pivotally connected to the stationary part and inclosing and adapted to engage the ratchet wheel, such pawl being formed with a hand-hold.
4. The combination with a shaft to be rotated presenting a polygonal portion, of means for intermittently rotating the same comprising a spanner adapted to engage such polygonal portion, a device rotatably mounted upon the shaft and presenting a projecting portion adapted to rotatably support the spanner out of engagement with the shaft, and means formed partially on the said device and partially on the spanner for preventing the disconnection of the spanner from the said device except in one angular position.
5. The combination with a shaft to be rotated presenting a polygonal portion, of means for intermittently rotating the same comprising a spanner adapted to engage such polygonal portion, a device rotatably mounted upon the shaft and presenting a projecting portion with a diagonal slot and adapted to

rotatably support the spanner out of engagement with the shaft and a trunnion with an oval head formed on the spanner and engaging in the slot for preventing the disconnection of the spanner from the said device except in one angular position.

6. In a shaft rotating device, a two piece strap for carrying means for manually rotating the shaft, such strap pieces being formed at one end to interlock, and one of the pieces being formed with a tubular stud and the other with a hole to receive the end of such stud and have the same expanded therein.

7. In a shaft rotating device, a two piece strap for carrying means for manually rotating the shaft, such strap pieces being formed at one end to interlock, and one of the pieces being formed with a tubular stud with one end diminished, and the other with a hole to receive the said diminished end and have the same expanded therein.

8. In a shaft rotating device, a two piece strap for carrying means for manually rotating the shaft, such strap pieces being formed at one end to interlock, and one of the pieces being formed with a hole and a tubular stud concentric with such hole and having one end diminished and the other with a hole to receive the said diminished end and have the same expanded therein.

In testimony whereof, I have signed my name to this specification, in the presence of two subscribing witnesses.

OTTO WILLIAM MEISSNER.
